UNITED STATES PATENT OFFICE.

CARL RECHT, OF BROOKLYN, NEW YORK.

SHEET-METAL-PIPE JOINT.

SPECIFICATION forming part of Letters Patent No. 277,427, dated May 8, 1883.

Application filed July 29, 1882. (No model.)

To all whom it may concern:

Be it known that I, CARL RECHT, a citizen of the United States, residing at Brooklyn, in the county of Kings and State of New York, 5 have invented new and useful Improvements in the Method of Uniting the Ends of Sheet-Metal Pipes, of which the following is a specification.

This invention relates to an improved method of uniting the ends of sheet-metal-pipe sections; and it consists, essentially, in inserting one piece of pipe into the other and forming simultaneously on both pieces a series of projections. This joint may be further improved 15 by pressing down the projections formed as above stated.

In the accompanying drawings, Figure 1 represents a side elevation of my joint. Fig. 2 is a longitudinal section of the same on a 20 larger scale than the previous figure. Fig. 3 is a similar section of my joint when the projections have been pressed down.

Similar letters indicate corresponding parts.

In the drawings, the letter A designates a 25 sheet-metal pipe, the end of which is inserted into another pipe, B, as shown in Figs. 2 and 3. After the piece A has been thus inserted into the piece B, I produce on both pieces simultaneously a series of projections, a. This 30 object may be attained by a roller or other suitable tool, which will readily suggest itself to a skillful mechanic.

In the example shown in the drawings the 35 projections a extend outward; but, if desired, they may be made to extend inward. I prefer, however, to make the projections as shown in the drawings, since the same, if projecting outward, assume the form of blind rivets, thereby imparting to the joint a good appearance.

40 In order to improve the strength of my joint,

I press the projections a down, as shown in Fig. 3. For this purpose I introduce into the piece A a mandrel, of iron, closely fitting the pipe, and then I drive the projections a down by means of a punch, C. (See Fig. 3.) By 45 these means the interior of the joint is left nearly smooth, and the connection between the pieces A B is rendered very firm and durable.

What I claim as new, and desire to secure 50 by Letters Patent, is—

1. The method herein described for uniting the ends of sheet-metal-pipe sections, which consists in inserting the end of one pipe-section into another, and then forming simultaneously around both sections a series of projections which respectively interlock each other, substantially as set forth.

2. The method herein described of uniting the ends of sheet-metal-pipe sections, which 60 consists in inserting the end of one section into another, then forming simultaneously around both sections a series of projections which respectively interlock each other, and finally 65 pressing down the projections, substantially as set forth.

3. The combination of the pipe-section A with the pipe-section B, one inserted within the other, and confined by means of a series of 70 projections projecting laterally from both sections, and respectively interlocking with each other, substantially as described.

In testimony whereof I have hereunto set my hand and seal in the presence of two subscribing witnesses.
